DESIGN FOR AN ENVELOPE OPENER OR SIMILAR ARTICLE

Willis H. Miller, Dallas, Tex.

Application September 19, 1946, Serial No. 133,419

Term of patent 3½ years

(Cl. D74—1)

To all whom it may concern:

Be it known that I, Willis H. Miller, a citizen of the United States, residing at Dallas, in the county of Dallas and State of Texas, have invented a new original and ornamental Design for an Envelope Opener or Similar Article, of which the following is a specification, reference being had to the accompanying drawing, forming part thereof.

Figure 1 is a side elevational view of an envelope opener or similar article, showing my new design.

Figure 2 is an edge elevational view.

Figure 3 is a side elevational view of the opposite side shown in Figure 1, and

Figure 4 is a top plan view.

I claim:

The ornamental design for an envelope opener or similar article, substantially as shown.

WILLIS H. MILLER.
